UNITED STATES PATENT OFFICE.

ZEPHANIAH F. MAGILL, OF TROY, NEW YORK.

PORTABLE HEAD-REST.

SPECIFICATION forming part of Letters Patent No. 468,505, dated February 9, 1892.

Application filed August 7, 1891. Serial No. 401,953. (No model.)

To all whom it may concern:

Be it known that I, ZEPHANIAH F. MAGILL, a citizen of the United States, residing at Troy, county of Rensselaer, and State of New York, 5 have invented certain new and useful Improvements in Portable Head-Rests, of which the following is a specification.

My invention relates to such improvements; and it consists of the novel construction and 10 combination of parts hereinafter described and subsequently claimed.

Reference may be had to the accompanying drawings, and the letters of reference marked thereon, which form a part of this specification.

Similar letters refer to similar parts in the 15 several figures therein.

Figure 1 is a side view of the device with handle closed. Fig. 2 is a similar view with 20 handle extended. Fig. 3 is a side view showing a modification of handle. Fig. 4 is a cross-section on line 6 6, Fig. 1. Fig. 5 is a cross-section on line 7 7 of Fig. 3; and Fig. 6 is a 25 partial front elevation, the parts being in the situation indicated in Fig. 2.

My improved device consists of a standard A, provided with a concaved foot A' on one end, adapted to rest upon the back of a seat, and at the other end with a cushion-rest A² 30 for the head of a person in a devotional attitude. The cushion-rest may be concaved, as shown, to fit the forehead of the person, and the device may be wholly or in part upholstered or ornamented in any known manner, 35 as desired. The cushion-rest serves to form a head-support and may be of any desired form, although I prefer to elongate it in a direction extending crosswise of the forehead.

C is a folding handle hinged to the standard 40 by the pin C', supported by the ears C², secured to the standard, as by rivets C³. The handle is provided with a longitudinal slot C⁴, adapted to receive and form a slideway for the pin. When in use, the handle is swung 45 out at right angles to the standard, with the pin at the inner end of the slot, as shown in Fig. 2. For convenience in transportation, when not in use, the handle is folded against

the standard. When desired, the pin which passes through the handle-slot may also pass 50 through an aperture in the standard itself, as shown in Figs. 3 and 5, and the handle be clamped in the desired position by means of a thumb-nut D. The pin has a head D' on one end, adapted to engage the handle, and 55 screw-threads D² on the other end, adapted to enter and fit similar threads in the nut. The handle can be swung and slid from the folded position shown by the solid lines in Fig. 3 to the position shown by dotted lines in the 60 same figure, and clamped in such position by turning the nut tightly against the standard or a washer D³, interposed between the standard and nut. A washer D⁴ may also be interposed between the standard and handle. 65

I am thus able to provide a convenient portable head-rest which will afford a comfortable support for the head while in a devotional attitude, as at prayer during church services.

What I claim as new, and desire to secure 70 by Letters Patent, is—

1. In a portable head-rest, the combination, with a standard having a concaved foot on one end and a rigid head-support on the other, of a slotted handle hinged to the standard 75 and extending at right angles to the head-rest and adapted to be folded parallel with the standard, and means for securing said handle in any desired position, substantially as set forth.

2. In a portable head-rest, the combination of a standard having a convexed foot on one end and a transversely-arranged concaved head on the other end, a handle having a slot C⁴, and a pin passing through said slot and 85 connected with the standard, the handle being adapted to swing about the pin in a plane transverse to the head and to be moved lengthwise thereon.

In testimony whereof I have hereunto set 90 my hand this 3d day of July, 1891.

ZEPHANIAH F. MAGILL.
